UNITED STATES PATENT OFFICE.

HUGH J. McMACKIN, OF BOSTON, MASSACHUSETTS.

PASTING-MACHINE.

1,144,717.

Specification of Letters Patent. Patented June 29, 1915.

Application filed February 28, 1914. Serial No. 821,828.

To all whom it may concern:

Be it known that I, HUGH J. McMACKIN, a citizen of the United States, residing at Boston, county of Suffolk, State of Massachusetts, have invented an Improvement in Pasting-Machines, of which the following description, in connection with the accompanying drawing, is a specification, like characters on the drawing representing like parts.

This invention relates to pasting machines adapted for applying paste to labels which are to be subsequently applied to cartons, cans, boxes, etc., and the object of the invention is to provide a novel device of this class which is simple and inexpensive to manufacture, the parts of which can be readily disassembled, thus facilitating greatly the cleaning of the machine and by which labels can be rapidly and efficiently supplied with a coating of paste, and otherwise to improve pasting machines, all as will be more fully hereinafter described and then pointed out in the appended claims.

Figure 1 is a sectional view through a pasting machine embodying my invention; Fig. 2 is a plan view of Fig. 1; Fig. 3 is an end view; Fig. 4 is a section on substantially the line $x-x$, Fig. 3; Fig. 5 is a section on substantially the line $y-y$, Fig. 3; Fig. 6 is a fragmentary perspective view of the wiping pad.

The device herein illustrated is of that type which comprises a frame sustaining a paste-receiving reservoir, a pasting roller journaled in the frame and by which the paste is supplied to the labels or other articles to be pasted, a shaft situated above the pasting roller and provided with disks that rest on the roller and which serve to hold the label against the pasting roller while it is being pasted, and means to operate the roller and disk-carrying shaft.

In the drawings 1 designates the frame of the machine which is provided with two end members 2 and which also is formed with a paste-receiving reservoir 3. I will preferably make the frame in the form of a casting so that the end members and the paste-receiving reservoir all form integral parts of the same casting. The end members are each provided with upwardly-di-

rected extensions 4, each of which is provided with a vertical slot 5, said slots operating to receive both the shafts of the pasting roller and that of the disk. The pasting roller is shown at 6, it being provided with journals 7 that occupy the slots 5, and these journals will preferably be provided with collars 8 to hold the pasting roller 60 against longitudinal movement. This roller can be operated in any suitable way as by means of the handle 9.

10 designates the shaft which supports the disks 11 that bear on the pasting roller, the ends of said shaft 10 being received in the upper ends of the slots 5. I will preferably provide means for positively rotating the disk shaft 10, this being herein accomplished by providing said shaft with a gearing 12 that meshes with a gear 13 rigid with the pasting roller 6. The frame 1 is so cast that the paste-receiving reservoir 3 is open at the top, and this opening is normally closed by a cover 14 which also constitutes a platform 75 on which the label to be pasted rests as it is fed into the machine. This cover may be held in place in any suitable way as by means of spring catches 15.

In using a device of this sort, the label to be pasted is placed on the platform or cover 14 with the face side up and the side to be pasted resting on the platform, and by turning the pasting roller the label will be drawn in between the roller and the disks 11, and the roller will apply a layer of paste to the back side of the label.

It is desirable that the peripheries of the disks 11 should be kept free from paste in order to prevent their depositing paste on the front side of the label, and to thus keep them clear I propose to use a wiping pad 16 which yieldingly engages the top of the disks and keeps the peripheries thereof free from paste. This wiping pad is herein shown as made of resilient material, such, for instance, as felt or rubber, and as confined within a holder 17 herein shown in the form of a tube which is cut away or slotted at one side, as at 18, to expose a portion of the pad 16. The pad 16 will preferably be so constructed that it will project slightly through the slot 18 in the holder, and the edges of the slots act as stops to prevent

the pad from being brought against the disks with undue pressure. This pad 16 and its holder 17 are shown as carried by arms 19 that are pivoted at their ends to the frame at 20, and the pad is yieldingly held against the disks by means of a spring 21 which encircles the pivot screws 20 and engages the arms 19. This construction permits the pad to be swung back out of the way of the disks when the latter are to be removed.

22 is a receiving platform on which the gummed or pasted label is received. This platform has a skeleton construction, it comprising a plurality of connected fingers 23, the ends of which are received in grooves 24 formed in the surface of the pasting roller 6. This platform 22 is provided at its outer end with trunnions or bearings 25 that are 20 journaled in notches 26 formed in extensions 27 on the end pieces 2 of the frame. By means of this construction the platform can be swung back out of the way when the pasting roller is to be removed for cleaning or 25 other purposes. This platform is yieldingly and removably held in the notches 26 by springs herein shown as part of the springs 21. In other words, the spring wire from which the spring 21 is formed is extended at 30 one end, as at 28, and provided with a hook portion which hooks over the trunnion 25. The same spring, therefore, operates to hold the platform in place and also to yieldingly hold the wiping pad against the disks. The 35 springs, however, can be readily disconnected from the trunnions 25 if the platform is to be removed.

29 designates a scraper which is adjustable toward and from the pasting roller and by 40 which the amount of paste carried up by the roller to the label can be regulated. This scraper is shown as pivotally mounted upon pivot pins 30 carried in the end pieces of the frame, and it is provided with an extension 45 31 extending through a slot in the frame and engaging a groove 32 in an adjusting screw 33 that is situated exterior of the end piece and has screw-threaded engagement with a lug 34 carried by the frame. By turning 50 the screw 33 up or down the scraper will be swung about its pivots, thus carrying its edge toward and from the periphery of the pasting roller.

One advantage of my construction is that 55 the shaft 10 carrying the disks and the pasting roller can be readily removed from the machine whenever the latter is to be cleaned, for it will be noted that both of these elements are journaled in the same open-ended 60 slots 5, and are only held in position by their own weight and by the pressure of the wiping pad thereagainst. The wiping pad can be readily swung back out of the way after which both the disk shaft 10 and the 65 pasting roller can be lifted from the slots

and cleaned, as also can the paste-receiving receptacle. This is quite an important item in devices of this class in which a sticky material, such as gum or paste, is used for unless they are frequently cleaned the machine soon gets gummed up to such an extent as to render it unfit for use.

70 My device is also well adapted for moistening gummed back labels. Many labels are supplied to the customer with the back 75 already gummed and the operation of putting the label on the box, carton or package involves moistening the gummed back of the label. By filling the receptacle 3 with water or some other moistening fluid, my device 80 can be used for moistening gummed back labels.

While I have illustrated herein a selected embodiment of my invention, I do not wish 85 to be limited to the constructional features shown.

Having described my invention, what I 90 claim as new and desire to secure by Letters Patent is:—

1. In a pasting machine, the combination 95 with a frame presenting end pieces and an open-topped paste-receiving reservoir between the end pieces, said end pieces each having an upwardly-directed extension provided with a single vertically-arranged open-ended slot extending from the top of the extension, of a pasting roller having trunnions which occupy said slots and is freely movable vertically therein, a disk-supporting shaft also journaled in said slots and provided with disks which rest on the pasting roller, a pad holder carrying a wiping pad which rests on the disks, arms pivoted to the end pieces and carrying the pad holder, springs engaging said arms and yieldingly holding the pad against the disks and a receiving platform supported at one end of the pasting roller and sustained at its other end on the frame, said springs engaging the platform and yieldingly holding 100 it in position.

2. In a pasting machine, the combination 105 with a frame presenting end pieces and an open-topped paste-receiving reservoir between the end pieces, said end pieces each having an upwardly-directed extension provided with a single vertically-arranged open-ended slot extending from the top of the extension and also having a second upwardly-directed extension provided with a 110 notch, of a pasting roller having trunnions which occupy said slots and is freely movable vertically therein, a disk-supporting shaft also journaled in said slots and provided with disks which rest on the pasting 115 roller, a pad holder carrying a wiping pad which rests on the disks, arms pivoted to the end pieces and carrying the pad holder, springs engaging said arms and yieldingly holding the pad against the disks, and a re- 120 125 130

ceiving platform supported at one end on
said pasting roller and having trunnions ex-
tending from the other end thereof, which
rest loosely in said notches, said springs hav-
ing extensions to engage the platform trun-
nions and retain them in the notches.

5 In testimony whereof, I have signed my

name to this specification, in the presence of
two subscribing witnesses.

HUGH J. McMACKIN.
